[57] **CLAIM**

The ornamental design for an intravenous supply container support or the like, as shown and described.

DESCRIPTION

FIG. 1 is a top perspective view of an intravenous supply container support or the like, showing my new design;

FIG. 2 is an enlarged perspective view thereof;

FIG. 3 is a front elevation thereof;

FIG. 4 is a side elevation thereof;

FIG. 5 is a top plan view thereof;

FIG. 6 is a bottom plan view thereof;

FIG. 7 is a cross-section taken on line 7—7 of FIG. 3; and

FIG. 8 is a cross-section taken on line 8—8 of FIG. 5. The broken lines are shown for illustrative purposes only.

FIG. -1**FIG. -2****FIG. -3****FIG. -4****FIG. -7****FIG. -5****FIG. -8****FIG. -6**
